J. French,

Bed Bottom,

Patented Aug. 25, 1831.

Josiah French Ware, Massachusetts 6728X

Seth's Patent

The Schedule referred to in this Seth's Patent, and making part of the same containing a description in the words of the said Josiah French himself of his improvement in the mode of making and manufacturing Beds by springs, called: Spring Beds.

It all purple to whom these presents shall come; Josiah French of Ware in the County of Hampden and State of Massachusetts Gentleman. Gents greeting. As is known to all the said Josiah French, have invented, constructed, made and appointed to use a new and useful improvement in making Beds called the Spring Beds Specified in the Schedule following viz: 1° The bottom is made of boards planed, and joined together with pins, leaving the boards of the length and breadth which may be required for any bed. 2° The Springs are made of wire about one eighth of an inch in diameter, the wire is bent round a cylinder which is four inches in diameter, but the wire round the cylinder is the proper height, so that Springs will be taken off the cylinder when bent, and a nail fastening and they can be made longer or shorter as may be required. The Springs after they are taken off the cylinder are bent and by cutting being turned round them to prevent any sound of the wire.

These Springs are set on the board in the following manner viz. The bottom end of the Spring is bent down about $\frac{1}{8}$ of an inch, and is bent back in the bottom the same side of the wire, and the Springs set in and a wire staple driven over the wire about half way round, near the place where it is bent in the bottom. The staple is to keep the Spring from turning on the bottom. The Springs to ~~fit~~ as near to each other as they can on the bottom board.

3° A frame of the side of the bed is made to receive the above Springs of board, high wood, one and one half inches wide and one inch thick to be put together on the same side of the bottom and to be placed half way between the bottom board and the top of the Springs. & attached to the bottom board by leather straps and such straps being of no other use than to prevent the frame from rising when drawing out the top board, and wires to keep the Springs perpendicular.

688

and to nail the top corner to 4" of corner of Cullen Bottom plank on
the top of the spring, 5" of corner of plank thick. Thick plank is known as the above
Cullen Bottom and nailed to the frame and nailed to the bottom board like
a 4" thick board of Cullen bottom or any kind of shiplap that will fit
is placed on the above deck and then a covering of Cullen hickory or any thing
not very large choice of a Bramble and nailed to the bottom board
which completes the deck.

I declare that the above is a true Specification of my said
improvement as above described. I have hereunto set my hand and seal the
Eight day of August in the Year of our Lord one thousand eight hundred
and thirty one.
